UNITED STATES PATENT OFFICE.

GEORGE HENRY WHEARY, OF RACINE, WISCONSIN, ASSIGNOR TO WHEARY-BURGE TRUNK COMPANY, OF RACINE, WISCONSIN, A CORPORATION OF WISCONSIN.

DESIGN FOR A WARDROBE TRUNK.

Application filed May 26, 1922. Serial No. 2,419. Term of patent 7 years.

To all whom it may concern:

Be it known that I, GEORGE HENRY WHEARY, a citizen of the United States, residing at Racine, in the county of Racine and State of Wisconsin, have invented a new, original and ornamental Design for Wardrobe Trunks, of which the following is a description, reference being had to the accompanying drawing forming part thereof.

The drawing shows a perspective view of a wardrobe trunk, showing my new design. I claim:

The ornamental design for a wardrobe trunk, as shown.

GEORGE HENRY WHEARY.
